Patented July 13, 1909

UNITED STATES PATENT OFFICE.

DAVID E. INGLE AND EDWIN H. INGLE, OF DAYTON, OHIO.

CHECK-CABINET.

No. 927,799.

Specification of Letters Patent.

Patented July 13, 1909.

Application filed May 14, 1909. Serial No. 495,885.

To all whom it may concern:

Be it known that we, DAVID E. INGLE and EDWIN H. INGLE, citizens of the United States, residing at Dayton, in the county of Montgomery and State of Ohio, have invented certain new and useful Improvements in Check-Cabinets; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in cabinets and comprises a check cabinet for use in retail stores where a credit business is done, especially in retail grocery stores.

The object of the invention is to provide a check cabinet which constitutes a convenient means for handling the checks which, when given to a customer has a money value which stands against him as a credit until the checks are all taken back by the store keeper, at which time, the credit is exhausted and the amount due is payable. The cabinet affords a convenient means for dispensing the checks and receiving them and does away with the necessity of keeping a book to denote the various sales and credits thereon, also obviates the necessity of adding columns of figures with the incidental risk of errors.

In the accompanying drawings, Figure 1, is a front elevation of our improved store keeper's check cabinet. Fig. 2, is a vertical sectional elevation thereof on the line *a a* of Fig. 1.

In a detail description of the invention, similar reference characters indicate corresponding parts.

The cabinet consists of two united parts, to-wit: a base portion 1 and an upper frame portion 2, the entire cabinet being of any suitable ornamental design and preferably constructed of wood. The upper portion of the base forms a suitable counter or shelf for the cabinet, and below said counter or shelf may be provided any suitable number of drawers in which to contain the various checks, said drawers being provided with lock and key. The upper portion of the cabinet consists of a back which extends from the back of the base portion, and sides 3, which are joined by cross pieces 4, a top 5

and a front ornamental panel 6. Supported between the cross-pieces 4 4 are a series of cheek tubes 7 which are preferably of glass or any other transparent material, and entrance 60 to the upper ends of these tubes or cylinders, is provided by means of a series of flaring tubes 8 which communicate with the extreme top 5 of the cabinet through openings 9 in said top. The chips or checks 10 are dropped 65 into the tubes through the upper ends or openings as received from customers, and each of said tubes is of sufficient diameter to contain a definite number of the chips or checks. For example, in Fig. 1, the tube of 70 the greatest diameter is designed to contain checks corresponding in size to a silver dollar, while the tube of a smaller diameter is intended for chips or checks corresponding in size to a ten cent piece. The money value 75 of each lot of checks or chips so placed in said tubes is inscribed upon the front sides of said tubes, also on the face of the checks, and owing to the transparent nature of the tubes, the decreasing or increasing number of checks 80 or the money value thereof may be at any time observed from the height of the stack of checks within the tubes and the indications on the tubes.

It will be understood that the checks or 85 chips 10 as shown in Fig. 2, and designed for use in the cabinet, may be constructed of sheet metal or celluloid; the valve of each series of checks being stamped thereon, for example, the dollar series of checks having 90 \$1.00 stamped thereon, while the series of checks representing cent values have stamped thereon 1¢ etc.

Extending entirely across the cabinet at a suitable point below the lower ends of the 95 tubes, is a stationary plate 12 having its front edge 13 turned down. This plate 12 affords a support for a series of individual slides 14 which lie immediately below the tubes and upon which rest the stacks of 100 chips within said tubes. The rearward ends 17 of these slides are turned down so as to form a shoulder which is engaged by the cross plate 12 and thus the slides are prevented from being drawn too far forwardly from 105 beneath the tubes in removing the checks, for example, in giving change. The said slides 14 extend a sufficient distance in front of the tubes to provide a down-turned finger-piece 15 by means of which said slides are 110 drawn out in removing the checks. Each of the slides 14 has a recess 16 in its upper side

into which the checks lie. The said slides are maintained in the inner or normal position shown in Fig. 2 by a spring 18, one end of which is secured to the down-turned edge 5 13 of the plate 12, and the other end of which is attached to the down-turned end 17 of the slide.

In using the cabinet, each clerk is assigned with a drawer A B D or E with a certain 10 amount of checks therein. When a customer who is in the habit of receiving credit comes or sends to the store for an article, and is free from debt or his credit is extended, such person is given a supply of checks representing a certain money value, say for example, \$5.00, and a check credit slip is made out by the clerk with the name of such person thereon and the money value of the checks given, and is placed in the drawer of 15 that particular clerk. These checks are subsequently received from such person or others sent to the store by him, in payment for goods until said checks are exhausted. As the checks are received, they are dropped 20 into the tubes according to their face value, and at the end of the day the amount of sales or business done may be ascertained by looking at the tubes to discover how many checks have been delivered thereto during 25 the day's business. The drawers contain the paper slips indicating the amount of credit outstanding.

We claim:

A credit system cabinet comprising base

and upright portions, the base having a series of drawers therein, and the upright portions having a series of cross strips, a series of vertical transparent tubes of varying diameters mounted between said cross strips, said tubes communicating at their upper ends with flaring openings which extend through the top of the cabinet, a stationary plate below said tubes having its front edge turned downwardly, a series of slides supported upon said plate at the lower ends of the tubes, said slides having depressions adapted to receive the checks from the tubes when said slides are pressed inwardly, the outer ends of said slides being turned downwardly to provide means for pressing 50 said slides inwardly and for indicating the value of the checks removed thereby, the rearward ends of said slides being turned downwardly to engage the cross plate and to thus limit the outward movements of said slides, and a series of springs attached to the cross plate and to the down-turned ends of the slides and serving to move said slides to their outer positions in delivering the checks from the tubes. 60

In testimony whereof we affix our signatures, in presence of two witnesses.

DAVID E. INGLE.
EDWIN H. INGLE.
